UNITED STATES PATENT OFFICE.

CLINTON J. G. RICKERSON, OF LOS ANGELES, CALIFORNIA.

CAR-COUPING.

Specification of Letters Patent.

Patented Apr. 18, 1916.

1,179,650.

Application filed July 28, 1915. Serial No. 42,316.

To all whom it may concern:

Be it known that I, CLINTON J. G. RICKERSON, a citizen of the United States, residing at Los Angeles, in the county of Los Angeles and State of California, have invented certain new and useful Improvements in Car-Couplings, of which the following is a specification.

This invention relates to improvements in car couplers and particularly to couplers so constructed that they may be coupled or uncoupled and the knuckles be set for coupling without the necessity of getting between the cars.

15 It is an object of the invention to provide a car coupler in which the coupling knuckle may be released for uncoupling cars no matter whether there is a pulling strain upon the coupling or not.

20 It is also an object of the invention to provide a coupler having latching means for holding the knuckle in close position which have a toggle like action whereby the parts may be released irrespective of any pull 25 upon the coupler.

It is also an object of the invention to provide such a coupler with means coöperating with the uncoupling means for setting the knuckle in open position and in readiness for the next coupling operation.

In the accompanying drawing forming a part of this specification: Figure 1 is a horizontal sectional view taken through the car coupler so as to show the knuckle locking and operating means, the shank or stem of the coupler being shown in top plan view. Fig. 2 is a vertical transverse sectional view taken upon the line 2—2 of Fig. 1. Fig. 3 is a detail horizontal sectional view similar 35 to Fig. 1 but showing only a portion of the coupler and illustrating the position of the parts when the knuckle is thrown open and in readiness for coupling. Fig. 4 is a transverse sectional view similar to Fig. 2 but 40 illustrating the knuckle locking and opening means in the position assumed when the said knuckle is open. Fig. 5 is a fragmentary detail sectional view showing the adjacent ends of the toggle like latch pieces 45 provided with intermeshing corrugations 50 upon the meeting ends thereof.

The details and features of the invention will now be more specifically described and claimed reference being had to the accompanying drawing in which 5 indicates a coupler and 6 the knuckle thereof, pivotally se-

cured in position within the head of the coupler by the usual pivot pin 7, the end contour of the coupler head at 8 is shaped in the usual way for receiving and closely fitting upon the knuckle of the coupler upon an adjacent car and the form of the said coupler and of the knuckle 6 is preferably made in accordance with the usual Master Car Builders' design.

In the present coupler the tongue 9 of the knuckle is made substantially as in car couplers made in accordance with the Master Car Builders' design, a projection 10 however being added to the inner end or point thereof for permitting of the throwing open of the knuckle as will be hereinafter more fully described. The locking of the said knuckle 6 and the means for throwing the knuckle into open position form important parts of the present invention.

The locking means preferably comprises a sliding member or bolt 11 having the recesses 12 therein adapted to receive the end of the tongue 9 and the projection or heel 10 thereof. The said locking member is arranged to move in a passage 13 which extends transversely of the coupler head, the said passage forming a guide way for the movement of the member 11. The member 11 is adapted to be held and locked in tongue holding position by

means of latch members 14 and 15 which are applied preferably in alinement with the said member 11 and which have a toggle like action in controlling the operation of the said member 11. The opposite outer ends of the said latch members 14 and 15 are pivotally mounted so that the said members may rock with respect to each other when raised, their inner ends being applied together and adapted to come opposite each other when said members are depressed for blocking the inward movement of the said member 11.

The said outer latch member 15 is provided with oppositely protecting trunnions 16 adapted to engage recesses 17 formed at the outer ends of the passage way 13, the said recesses being opened at the top for facilitating the putting of the latch member 15 in position when the parts of the coupling are assembled. The other latch member 14 is similarly pivoted but is carried by the tongue holding member 11.

The said member is provided with end projections 18 and 19 extending from each side thereof and having recesses 20 therein adapted to receive trunnions 21 which pro-

ject from the sides of the latch member 14. The said projections 19 and 20 move in the said passage way 13 with the tongue holding member 11, the said member however being of a slightly less width and being guided by ledges 22 and 23 formed in the upper and lower corner portions of said passage way 13 as will be clearly understood by reference to the drawing.

10 When the knuckle is in closed position as shown in Fig. 1, it is locked against opening by means of the latch members 14 and 15 which fall into the position shown in Fig. 2 so as to chock any movement in the member 11 with a toggle like action. The toggle acting device thus employed can only be broken for releasing the member 11 and permitting of the uncoupling operation by the lifting of the meeting ends of the said members 14 and 15 so that they may fold upwardly as shown in Fig. 4 and thus permit the tongue holding member 11 to slide inwardly. When the said member is at its inward position the tongue with the projection 10 thereon is free to swing outwardly for the opening of the knuckle, as will be clearly understood by reference to Fig. 3. In order to operate the said latch members 14 and 15 a lifting member or pin 24 is provided and arranged to move up and down in an opening 25 formed in the coupler head. The upper end of said pin is preferably rounded so that the ends of said latch members 14 and 15 will move easily thereon. The abutting ends of said members 14 and 15 are free to rise with the pin 24. The end of the member 14 adjacent to the bolt or member 11 is prevented from rising by a projecting portion 42 thereon, which engages an overhanging flange or projection 43 on said member 11. The outer end of the member 15 will not be lifted by the pin 24 because of the depth of the recesses 17 and their relation to the walls of the coupler head. The lower end of the pin 24 is provided with a head having an opening 26 therein through which a lever 27 is passed, one end of said lever being pivoted at 28 between depending lugs 29 upon the under side of the coupler head.

45 The opposite end of the lever 27 is curved upwardly and is bifurcated to receive a knuckle opening member 30. The said knuckle opening member 30 is pivoted at 31 in the bifurcated end of the lever 27 and is formed at its outer end with an eye or loop 32 which may be connected by a link or chain with any ordinary lifting mechanism placed upon the end of the car and not shown in the drawing. The inner end of

50 the said member 30 is made of sufficient length to reach well into the passage way 13 and to extend to the position shown in Fig. 4, for pushing the tongue holding member 11 inwardly and positively throwing the

55 knuckle into open position. In order to pre-

vent the member 30 from dropping out of its proper place its inner end is provided with oppositely projecting bosses 33, to catch upon the inner faces of flanges 34 which receive the said member 30 between them, forming a slot through which the said member operates. To facilitate the assembling of the parts of the coupler the end of the passage way 13 adjacent to the member 30 is normally closed by the removable plate 35, which is generally secured in place by any suitable bolts 36, and the flanges 34 are generally carried by said plate. The said member 30 can thus be pulled outwardly until the bosses 33 engage the flanges 34 but the said flanges and the closed lower ends of recesses formed thereby prevent the member 30 from falling out of operative position. The lever 28 also carries means for preventing the pin 24 from sliding under the same too far when the parts are in their lower position, such means being usually in the form of the boss or projection 37 formed upon one side of said lever 27.

In operation the knuckle 16 having been left in the open position shown in Fig. 3 is in readiness for coupling with the coupler of an adjacent car. In this position the latch members 14 and 15 are folded upwardly as illustrated in Fig. 4 and the tongue holding member is at the inner extreme of its movement as illustrated in Figs. 3 and 4. When in this position the opening in the member 11 is in position to receive the projection 10 and the end of the tongue 9 which carries the same. The lever 27 and the knuckle opening member 30 will have dropped back to the position shown in Fig. 2 carrying the pin 24 with them to its lowered position. When the said knuckle 6 is forced to its coupled position, as in a coupling operation, the tongue 8 swings into the recesses in the member 11 and the projection 10 thereon pushes the said member 11 to the outer extreme of its movement until the said knuckle has reached its coupled position. By this time the member 11 will have moved far enough for the latch members 14 and 15 to drop opposite each other in their lowermost positions and so that they fall a little below a plane passed through their pivot points. They will thus positively lock the tongue engaging member 11 and the said knuckle in its closed position. When it is necessary to uncouple the device the operator from one or the other side of the car operates the lifting mechanism and thereby pulls the eye 32 upwardly. The inner end of the member 30 slides upwardly and upon the end of the member 11, the lever 27 being at the same time raised, so that the pin 24 is lifted for breaking the toggle like latch mechanism and permitting the members 14 and 15 to fold. A continued lifting of the member

30 forces the inner end thereof into the passage way 13, so that the member 11 is positively pushed far enough to cause it to push upon the projection 10 carried by the tongue 9 and thus insure a full opening of the 5 knuckle 6. After thus uncoupling the knuckle the lever 27 with the pin 24 and the member 30 drop into their lowered positions again, and the parts are in position for the 10 next coupling of the device.

It will be evident that the minor details of construction may be considerably varied within the spirit and scope of the invention, and that mechanical equivalents of the various parts of the coupler may be substituted therefor if desired.

As shown in Fig. 5 the meeting ends of latch members as 38 and 39 may be corrugated or serrated as at 40 and 41 whereby 20 their meeting edges will not be able to slip by each other.

It will be observed that in the coupler of the present invention the means for locking the coupler knuckle in coupling position is easily 25 operated for releasing the knuckle in the uncoupling operation. The mechanism is so constructed that it can be readily operated even when a pulling strain is still exerted upon the coupler, thus avoiding the necessity of backing up the cars or rolling stock 30 in order to ease up on the couplers in readiness for the uncoupling operation as has been heretofore required with couplers in use.

What is claimed is:

35 1. A car coupler comprising a head, a knuckle having a holding tongue, a tongue holding member capable of controlling said tongue and a gravity actuated folding latch mechanism for locking the said holding member when retaining the knuckle in closed position.

2. A car coupler having a pivoted knuckle, a reciprocating bolt adapted to engage the said knuckle for holding it and independent 45 abutment members, adapted to come into alinement with each other for locking the said bolt.

3. In a car coupler provided with a pivoted knuckle, a recessed holding member 50 adapted to receive the tongue of the coupler and disconnected latch members adapted to come into alinement with each other for locking the said holding member and retaining the knuckle in coupled position.

55 4. A car coupler having a coupling knuckle provided with a locking tongue, a transverse bolt having a recess provided with a locking shoulder adapted to engage said tongue, and independent latch members interposed be-

60 tween the said bolt and the body portion of the coupler and coöperating for locking the bolt when the knuckle is in coupled position.

5. A car coupler having a pivoted knuckle, a bolt for holding the same, pivoted latch 65 members adapted to be brought in end to

end alinement with each other for locking the bolt and a release member adapted to throw the free ends of said latch members apart for releasing the bolt.

6. A coupler having a pivoted knuckle, a bolt 70 for holding the knuckle, end to end rocking members adapted to come together at their free ends for controlling the movement of said bolt, and a pin adapted to throw said free ends apart for releasing the bolt. 75

7. A car coupler comprising a head having a knuckle pivoted therein and provided with a transverse passage, a transversely moving bolt mounted in said passage and having a recess for engaging the tongue of the knuckle, said bolt being also provided with a latch engaging socket, a latch member movably engaging said socket and an opposing latch member shouldered in the head of the coupler, the structure being such 80 that when the latch members are brought into alinement with each other with their ends opposing, the bolt is locked against movement and when the latch members are bowed to one side the bolt is released. 90

8. A car coupler comprising a head and a knuckle pivoted therein and having a tongue formed with a locking end portion and a bolt actuating face, a bolt movably mounted in said head and having a socket engaging the bolt moving face of the said tongue and having a shoulder adapted to engage the locking end of the said tongue, articulating latch members interposed between the head and the said bolt and means for moving said latch members for releasing the bolt and permitting the knuckle to uncouple. 95

9. A car coupler having a pivoted knuckle and a transversely moving bolt provided with a recess for receiving the tongue of the coupler, said recess having a tongue holding shoulder, a latch member journaled in the socket formed in said bolt, an opposing latch member journaled in the head of the coupler, the adjacent ends of the said latch members 105 being adapted to rock upon each other for releasing the bolt, a pin having a head for rocking said latch members and a lever for moving said pin. 110

10. A car coupler having a pivoted knuckle, a tongue engaging member having a recess for receiving the said tongue of said knuckle and means for locking said holding member in tongue holding position, means for releasing said locking mechanism and means operating in conjunction therewith for positively moving the said tongue holding member and positively moving the tongue so as to open the coupler. 115

11. A coupling for cars comprising a coupler head having a transversely movable knuckle holding member provided with a recess therein adapted to receive the tongue of the knuckle, a knuckle pivoted in said head and having a tongue adapted to engage 120 125 130

the opening in said holding member and having a projection also entering the said recess whereby the tongue may be moved to open the coupler when the holding member is moved inwardly and a member adapted to push the said holding member inwardly when the coupler is uncoupled.

Copies of this patent may be obtained for five cents each, by addressing the "Commissioner of Patents, Washington, D. C."

In testimony whereof, I have hereunto set my hand, in presence of two witnesses.

CLINTON J. G. RICKERSON.
